[57]**CLAIM**

The ornamental design for an illuminated headband, as shown and described.

DESCRIPTION

FIG. 1 is a front elevational view of an illuminated headband showing my new design;

FIG. 2 is a top elevational view thereof;

FIG. 3 is a rear elevational view thereof;

FIG. 4 is an end elevational view thereof;

FIG. 5 is a perspective view thereof showing the headband as proposed to be worn by a wearer; and,

FIG. 6 is a sectional view taken along line 6—6 of FIG. 1.

The broken line showing of the human form, cord, battery pack, and clip in FIG. 5 is for illustrative purposes only and forms no part of the claimed design.
